UNITED STATES PATENT OFFICE.

FRED W. ROLLINS, OF EXETER, NEW HAMPSHIRE.

DESIGN FOR A DIRECTION-INDICATOR CASING.

Application filed September 27, 1924. Serial No. 10,917. Term of patent 3½ years.

To all whom it may concern:

Be it known that I, FRED W. ROLLINS, a citizen of the United States, residing at Exeter, in the county of Rockingham and State of New Hampshire, have invented a new, original, and ornamental Design for a Direction-Indicator Casing, of which the following is a specification, reference being had to the accompanying drawing, forming part thereof.

Fig. 1 is a front elevation of a direction indicator casing showing my new design and Fig. 2 is a side elevation thereof.

I claim:

The ornamental design for a direction indicator casing, as shown.

FRED W. ROLLINS.
